UNITED STATES PATENT OFFICE.

HARRY S. HART, OF CHICAGO, ILLINOIS.

DUMP-CAR.

1,304,969.

Specification of Letters Patent. Patented May 27, 1919.

Application filed October 21, 1918. Serial No. 258,989.

To all whom it may concern:

Be it known that I, HARRY S. HART, a citizen of the United States, residing at Chicago, in the county of Cook and State of Illinois, have invented certain new and useful Improvements in Dump-Cars, of which the following is a specification.

This invention relates to dump cars.

The object of this invention is to improve dump car construction in a novel and simple manner to increase the capacity thereof and at the same time retain the self-cleaning feature.

This and other objects are accomplished by means of the arrangement disclosed by the accompanying sheets of drawings, in which—

Figure 1 is a fragmentary side elevation of a dump car embodying my invention;

Fig. 2 is a fragmentary plan view of the same dump car; and,

Fig. 3 is a transverse sectional view of the dump car taken over the trucks.

In these days of extremely congested rail-way and heavy traffic conditions, the importance of increasing the capacity of rail-way cars has become recognized, this probably being especially true in connection with dump cars for carrying coal and other dumpable materials.

In a certain well known type of dump car, the floor at each end of the car over the trucks includes a long sloping member extending downwardly from the end of the car near the top thereof toward the transverse center of the car to form one wall of a transversely extending hopper, the center of the car being provided with a transversely arranged A portion including

transversely arranged dump doors forming the other wall for each of these hoppers arranged on either side of the transverse center line of the car. In other words, this well known type of dump car includes two

transversely arranged hoppers, the walls of which are formed by a transversely arranged A portion in the middle of the car and with long sloping members at the ends of the car, said members extending downwardly and

toward the transverse center of the car.

By referring to the figures of the drawings, it will be noted that I have shown a dump car including sides 10, ends 11 and a floor, the floor portion over the trucks, and particularly between the ends 11 of the car and the associated bolsters 12, including A-

shaped portions 13. Preferably these A-shaped portions include sloping members 14 which extend from the center of the car over the center sill 15 downwardly and outwardly toward the sides of the car. These downwardly and outwardly sloping members 14 preferably are stationary and connected to the car underframe to increase the stiffness and rigidity of the car structure. These downwardly and outwardly sloping members 14 terminate in side exit openings which normally are closed by dump doors 16, which preferably are hinged at 17 along the lower edges of the sides 10 of the car, the swinging edges of the dump doors 16 meeting the lower edges of the members 14 to form a tight seal. The longitudinally extending dump doors 16 at the sides of the car may be operated by any suitable operating mechanism, including shafts 18, preferably carried by said dump doors, and also including chains 19 connecting said shafts with the floor portions 14. By providing this A-shaped floor portion over the trucks, the capacity of the car is greatly increased and at the same time the portion of the load over the trucks is effectively dumped to the sides of the car through the openings normally closed by the side dump doors 16, this portion of the car being entirely self-cleaning.

The floor construction intermediate the bolsters 12 includes a central transversely arranged A-shaped portion, the upper part 20 of which is stationary and the lower part 20 of which at each side of the A includes a transversely arranged dump door 21 transversely pivotally hung at 22. This transversely arranged A-shaped portion, including members 20 and doors 21, divides the car transversely into two hoppers 23, only one of which is shown in the figures of the drawings. In the case of each of these transversely arranged hoppers 23, one wall is formed by the transversely arranged members 20 and 21. The other transversely arranged wall is formed by a sloping member 24 which extends substantially from the inner end of the floor portion over the trucks and from the bolster 12, or at a point inwardly therefrom, downwardly toward the transverse center line of the car, the exit opening at the lower end of the member 24 normally being closed by the transverse dump door 21, which when closed forms a tight seal with the lower edge of the member 24. It will be understood that the dump

doors 21 forming portions of the transverse central A swing inwardly toward each other when moved into open position and outwardly away from each other when moved into closed position. The transverse dump doors 21 may be operated by any usual operating mechanism 25. That portion of the load which is not dumped to the sides of the car past the side doors 16 will be dumped 10 past the transverse dump doors 21 between the tracks and between the trucks, the car being self-cleaning throughout due to the sloped arrangement of all of the floor portions.

15 As stated above, by making the floor portions over the trucks in the form of longitudinally extending A-shaped members 13, the capacity of the car is effectively increased, and at the same time the self-cleaning 20 feature maintained.

It is my intention to cover all modifications of the invention falling within the spirit and scope of the following claims.

I claim:

- 25 1. A dump car having sides, ends and a floor, the floor portions over the trucks including members sloping downwardly and outwardly toward the sides of the car, the floor intermediate the trucks including hopper 30 members having transversely arranged dump doors which swing toward each other and away from each other into opened and closed positions, respectively.
- 35 2. A dump car having sides, ends and a floor, the floor portions over the trucks including members sloping downwardly and outwardly toward the sides of the car, the floor intermediate the trucks including hop-

per members, and dump doors associated with the floor portions over the trucks for dumping the load to the sides of the car, said hopper members including transversely arranged dump doors which swing toward each other and away from each other into opened and closed positions, respectively, whereby the remaining portion of the load may be dumped between the tracks and trucks.

3. A dump car having sides, ends and a floor, the floor portions over the trucks including members sloping downwardly and outwardly toward the sides of the car, the floor intermediate the trucks including hopper members, dump doors associated with the floor portions over the trucks for dumping the load to the sides of the car, said hopper members including transversely arranged dump doors which swing toward and away from each other into opened and closed positions, respectively, whereby the remaining portion of the load may be dumped between the trucks, and door operating mechanism whereby said dump doors may be operated.

4. A dump car having sides, ends and a floor, the floor over the trucks including A-shaped portions arranged to discharge the load toward the sides of the car, the remaining portion of the floor comprising hopper walls extending downwardly and toward each other, one from the transverse center of the car and the other from one of said A-shaped portions.

Signed at Chicago, Illinois, this 18th day of October, 1918.

HARRY S. HART.
